UNITED STATES PATENT OFFICE

2,633,610

PREFABRICATED HOUSE

David E. Hervey, Old Fort, N. C., assignor to
Hervey Foundation, Incorporated, a corpora-
tion of Maryland

Application August 27, 1946, Serial No. 693,242

1 Claim. (Cl. 20—2)

1

This invention relates to improvements in building construction and particularly to improved prefabricated houses and construction units therefor.

According to present practice in the construction of prefabricated houses certain types of standardized panels are provided for assembly according to any desired plan. Such standard types include wall panels, partition panels, floor panels, window panels, door panels, plumbing panels, and, in some cases, roof panels. These standardized panels are all of comparatively small size, about four feet by eight feet, being conventional, and a number of them must be secured together to provide any vertical or horizontal surface of the house. As they can be connected only at their adjacent edges by such means as interlocking splines or lugs a wall or floor surface made up of these panels alone would have no actual rigidity and insufficient truss strength to support itself and the panels of interconnected surfaces. It is therefore necessary in conventional practice to provide framing for at least certain portions of the house. Suitable floor and roof trusses are nearly always required to support the small floor and roof panels. In fact the usual practice is to supply only wall panels of prefabricated construction and construct the floor and roof on location in the conventional manner.

The present practice thus requires a substantially complete foundation wall and a large amount of skilled labor for the erection of the house. The size of available plywood or other suitable laminated material sheets has up to the present time imposed a definite limitation on the size of building panels that can be prefabricated.

In my copending allowed application Serial No. 693,243, filed August 27, 1946, for Press, I have disclosed suitable apparatus and a suitable method for producing laminated sheets of large size and for assembling such large size sheets with suitable framing to produce large truss panels.

In accordance with the present invention I purpose to construct each wall and partition of the house as a rigid, unitary, self-supporting panel and to provide floor and roof panels of such size that no auxiliary framing or trusses will be required.

It is an object of the present invention to provide improved structural units for prefabricated buildings wherein each unit is self-sustaining and may constitute an entire wall or partition or floor or roof surface and in which the entire building is composed of a small number of prefabricated structural units that can be quickly assembled, disassembled and reassembled, with a small amount of labor and supported on a small number of widely spaced foundation members.

A further object resides in the provision of im-

2

proved prefabricated building units interiorly braced so that the wall units are self-sustaining from end to end and support the partition, floor and roof units and the floor and roof units are of sufficient size and strength so that no auxiliary framing or trusses are required and all units are of a size such that joint lines are not present in the surfaces of the assembled building.

10 A still further object resides in the provision of improved structural units for prefabricated buildings wherein the units have framed door and window openings and all necessary plumbing and electric conduits and complete insulation in place therein before the units are delivered for assembly.

15 An additional object resides in the provision of improved connecting means for assembling prefabricated building units or panels whereby the various units or panels can be quickly and firmly secured together in a manner such that they can be disassembled without damage to the units if it should be desired to move or store the building.

20 Another object resides in the provision of a low cost prefabricated building providing adequate spacing and of durable construction and attractive appearance.

25 Still another object resides in the provision of a basic housing unit that can be expanded into a larger housing unit having larger rooms or a greater number of rooms without discarding any of the material of the basic unit.

30 Yet another object resides in the provision of an improved prefabricated building utilizing the largest size panels that can be effectively handled by present transportation facilities.

35 Another object resides in the provision of improved window construction for prefabricated buildings.

40 Another object resides in the provision of improved insulating material.

45 Another object resides in the provision of improved frame members constructed to resist dimensional changes incident to changes in moisture content.

Other objects and advantages will become apparent from the consideration of the following description and in conjunction with the accompanying drawings, wherein:

50 Fig. 1 is a plan view of a typical house illustrative of the invention;

Fig. 2, a perspective view of a house having a plan such as is shown in Fig. 1, portions being broken away to better illustrate the construction thereof;

Fig. 3, an elevational view of a structural unit constituting a wall member of the house with one of the plywood facings or covers omitted;

Fig. 4, an elevational view of the structural unit shown in Fig. 3 with the cover omitted in

Fig. 3 applied and patterns indicated for window, door and other openings;

Fig. 5, a plan view of a structural element constituting a part of the roof, a portion being broken away to better illustrate the construction thereof;

Fig. 6, an elevational view of an end wall member of the house, a portion being broken away to better illustrate the construction thereof;

Fig. 7, a perspective view of a floor unit and a fragmentary portion of an adjoining wall unit showing the manner of making electrical conduit connections between the two members;

Fig. 8, an elevational view of a structural unit constituting an interior partition, a portion being broken away to better show the construction of the roof;

Fig. 9, an elevational view of a structural unit constituting a different interior partition with the partition member shown in Fig. 8 illustrated in cross section;

Fig. 10, an isometric projection of one part of the connecting device by means of which adjoining structural members are secured together;

Fig. 10a, an isometric view of the mating part of the connecting device;

Fig. 11, a detailed view showing the manner of securing a roof panel to an exterior wall panel;

Fig. 12, a detailed view showing a manner of securing two roof panels together with the panels separated at their adjacent edges;

Fig. 13, a view similar to Fig. 12 showing the two roof panels drawn closely together and a seal provided along the peak of the roof;

Fig. 14, a detailed view showing the manner of securing the roof panels to an interior partition member;

Fig. 15, a detailed sectional view showing the manner of supporting the floor members from the wall members and of providing an electrical connection between a floor member and a wall member;

Fig. 16, an isometric view of a window constituting a unit of the improved building.

With continued reference to the drawings and particularly to Figs. 1 and 2, the invention contemplates a basic housing unit which may, if desired, be enlarged or expanded by the addition of structural members of a construction similar to those used for the basic unit without the necessity of discarding any of the material used to constitute the basic unit. Various room arrangements may be designed and the arrangement shown in Fig. 1 is merely illustrative of a typical arrangement of the rooms in a four room basic housing unit.

The unit comprises four outside wall members 1, 2, 3, and 4, two floor members 5 and 6, two roof members 7 and 8, a main interior partition member 9, and secondary partition members 10, 11, 12, 13, 14, and 15.

The house as illustrated has a corner window in each corner thereof, as indicated at 16, 17, 18, and 19; and side windows indicated at 20, 21, and 22, and an outside door is provided at 23.

Because of the novel construction of the various wall units, as will be later described, the entire house may be supported on four foundation posts, as indicated at 24, 25, 26 and 27.

Each wall and partition of the house is provided by a single prefabricated structural unit or panel and these panels are of a size that can be conveniently handled by present transportation facilities and yet when assembled will provide a housing unit exceeding the minimum

of spacial requirements set up by government agencies, such as the Federal Housing Administration and National Housing Agency, for housing units of this type. The illustrated unit provides a living room, a kitchen, two bedrooms BR1 and BR2, a bath room BA, closets C1, C2 and C3, and a storage closet SC, all of adequate size for comfortable and convenient use.

The construction of the front wall unit or panel 3 is particularly illustrated in Figs. 3 and 4. This structural unit has an interior frame comprising a plurality of longitudinal frame members 28, the upper three and the bottom one of which are continuous from one end of the panel to the other, the intermediate ones being disposed between the necessary window and door openings. Each window and door opening is completely surrounded by frame members, as indicated at 29 for the door opening and 30 for one of the corner window openings and these opening frames are rigidly secured to adjacent longitudinal frame members. The entire frame structure is braced by suitable trusses, as indicated at 31, 32, 33, and 34 so that it may be supported only at its ends and will have sufficient strength and rigidity to carry adjoining floor, roof and partition members without appreciable deflection. Continuous sheets 35 and 36 of laminated material, such as plywood, are applied one to each side of the frame and permanently bonded to the frame by suitable bonding material and also by fastening elements, such as nails or screws, if desired.

One of the facing or covering sheets, for example the outer sheet 36, has patterns on the openings marked thereon as indicated at 37, 38, 39 and 40 and after the panel is completely assembled the openings are cut out along these lines and the cut out portions are used for elements of the building so that there is no waste. For example, the portions cut out of the door openings are used for the doors and the portions cut out of the window openings may be used for shutters.

As stated above, the roof is provided by two structural units or panels, one of which is illustrated in detail in Fig. 5. This panel has an interior frame comprising a pair of continuous longitudinal members, one of which is indicated at 41 extending lengthwise of the panel for the full length thereof, and a pair of transverse or end members, one of which is indicated at 42, secured to the end of the longitudinal members. Between and parallel to the end members there are a plurality of spaced transverse members 43. The edge members may be heavier than the interior members 43, since the edge members will carry the means by which the panel is secured to the wall units of the building. Facings or coverings 44 and 45 of laminated material such as plywood are secured to the frame by bonding material and other fastening means as may be desired and a sheet 46 of weather resisting material, such as sheet aluminum, is securely bonded to the outer surface of one of the plywood covers. The metal sheet 46 projects outwardly beyond the frame and the plywood covers along all of the edges of the panel provide sufficient material along the edges to be bent over to form a complete cover for the edges of the panel.

A typical end wall for the building is illustrated in Fig. 6. This wall has an internal frame of longitudinal members 47 and truss bracings as indicated at 48 and 49, which provided sufficient strength and rigidity so that the end wall

also can be supported only at its ends and will support adjoining floor, roof and partition members without material deflection. The frame has a facing or covering of plywood on each side thereof secured to the frame bonding material, and additional fastening means if desired, the plywood coverings each constituting a single sheet as explained above in connection with Figs. 3 and 4. The window and door openings are marked as indicated above and are cut out when the panel is completely formed. Each end and each top edge of the end panels are provided with a series of projecting hooks 50, 51, 52, and 53, which cooperate with slots provided along the ends of the side panels 1 and 3 to secure the side panels to the end panels and with slots provided in the roof panels to secure the roof panels to the end panels. The specific construction of suitable hooks and slots is illustrated in detail in Figs. 10 and 10a.

Fig. 7 shows one of the two floor panels, for example the panel 5. These panels are somewhat similar in general construction to the roof panels except that they lack a sheet metal facing. Their internal frame comprises a pair of longitudinal edge members 54, a pair of end members 55, and a plurality of parallel spaced transverse members 56, which may be somewhat similar to the edge members. This frame is also covered on both sides by plywood facings 57 and 58. The inner facing 58 is made of comparatively heavy plywood stock and may if desired be provided with a surface layer of weather resistant material. Both facings are continuous and are secured to the frame by bonding material and other fastening means if desired. This panel may contain one or more suitable supports as indicated at 59 for plumbing pipes or other elements and may also contain an electric conduit 60 terminating in a plug member 61 engageable with a mating plug member 62 in an adjoining wall panel 1, so that the electrical connections for the house can be made at the time the house is assembled. Suitable electric conduits are placed in all of the panels at the time the panels are assembled and connecting plugs are suitably located so that the house circuits will be automatically completed when the house is assembled.

Fig. 8 illustrates the main interior partition member 9. This partition member has an internal frame comprising spaced parallel longitudinal members 63, vertical end members as indicated at 64, and truss bracing as indicated at 65 and 66, and on each side of the frame a facing or cover formed of a continuous sheet of plywood 67 and 68. This structural unit or panel also has sufficient strength so that it can be supported at its ends from the adjoining wall panels and will support adjoining floor and secondary partition panels without material deflection. A series of hooks, as indicated at 69 and 70 are provided one series along each end of the panel and one or more series of hook receiving slots, as indicated at 71 are provided in the face of the panel for the connection of the ends of secondary partition members thereto. Suitable door openings are framed in the framework of the panel and indicated on one of the face sheets at the time of assembly and one or more of which openings may be cut out to provide a door as desired. The cut out portion of the door opening may be used for the door in the manner described above.

The secondary partition panel or unit is illus-

trated in Fig. 9. This unit also has an internal frame comprising edge members as indicated at 72 and opposed parallel longitudinal members 73 and internal truss bracing 74 render the unit rigid and firm. The unit is provided with a door opening 75 in the manner indicated above and is provided along each edge with a series of hooks as indicated at 76 and 77. It will be noted that the hooks 76 are inverted, the reason for which will become apparent from the following description of the manner of assembling the units to construct the house.

The hook slots, as illustrated in Fig. 10 and indicated at 78, are provided as spaced apertures 15 in the web portion of a channel shaped member 79, which may conveniently be formed from sheet steel stock. The frame member 80 provided within the panel at the location of the hook receiving slots is provided with grooves or saw cuts which 20 receive the flanges 81 and 82 of the channel shaped member 79 and is provided between these saw cuts with a groove 83 of a width and depth sufficient to receive the hooks thereon. The panel is grooved along each side of the member 79 and 25 sealing members or gaskets 84 and 85 are seated respectively in these grooves to provide a tight joint between the connected structural units when they are forced together by the association of the hooks with the corresponding slots 78. The 30 member 79 is rigidly secured in place in the panel by suitable means, such as pins 86 extended through the panel frame member and through the flanges 81 and 82 of the channel shaped member 79.

35 The hooks, as illustrated in Fig. 10a, are struck up from the web portion of a channel shaped member 87 similar to the member 79, the flanges 88 and 89 of which are received in saw cuts provided in the edge portion of the panel frame member 90. The hooks 91 have slightly tapered surfaces engaging the portions of the member 79 between the hook receiving slots so that the weight of the hook carried wall will serve to continuously press this wall against the connected wall in which the hook receiving slots are provided. The member 87 is also secured in place by suitable screw pins, as indicated at 92.

When the house is to be assembled the foundation posts 24, 25, 26 and 27 are set and levelled. 50 The end walls 2 and 4 are then placed on the corresponding corner posts in a substantially vertical position. The main partition member 9 is then brought into position between the end walls and while elevated a slight distance above its 55 final position the hooks on the ends of the partition are inserted in corresponding apertures provided in the inner faces of the end walls 2 and 4. The partition member 9 is then dropped causing the hooks to pull the end walls tightly against the center partition member. Floor panels 5 and 6 are then placed in position and rest at their 60 edges on the upper surfaces of inwardly directed flange portions of angle irons, as indicated at 93 in Figs. 7 and 15 secured along the bottom edges 65 of the main partition panel and the end wall panels. The secondary partition panels are then placed in position and connected at their corresponding ends to the main partition panel and the end wall panels. The ends of the end walls 70 at the same side of the house will then be slightly elevated above their position of rest on the corresponding foundation posts and the corresponding side panel placed in position so that the hooks on the ends of the end wall panels will 75 be received in corresponding hook receiving slots

provided near the ends of the side panel and the inverted hooks 76 on the secondary partition panel connected to this side panel will be received in corresponding hook receiving apertures provided in the rear face of the side panel. When all of the hooks are in position in the corresponding hook receiving slots, the ends of the end walls are lowered and the weight of the end walls and other elements associated therewith will force the hooks into the slots in a manner to force the side wall firmly against the ends of the end walls and the secondary partition or partitions associated therewith. As the side wall is also provided with a floor panel supporting angle iron along the bottom edge thereof it will, of course, be necessary to raise the end wall ends sufficiently to insert the inwardly direct flange of this angle iron under the corresponding edge of the adjoining floor panel and when the end walls are lowered the floor panel will raise at all of its edges on angle iron flanges carried by the adjoining end walls, main partition wall and side wall.

The other side wall is connected to the associated panels in the same manner and the house will then be complete except for the application of the roof panels thereto.

The roof panels are placed in position such that hooks on the upper edges of the end walls and secondary partition members extend into corresponding hook receiving slots provided in the inner faces of the roof panels. When in this position the roof panels will be separated at their adjoining edges along the peak of the roof as indicated at 94 in Fig. 12.

Along the top edge of the main partition member 9 there is provided a series of spaced apart T-shaped members as indicated at 95 in Fig. 14, the stems of which are screw threaded and threaded into holes provided in the upper edge frame member of the partition member and the bar of which extends transversely through the partition member and has its opposite end portions 96 and 97 received in suitable apertures provided in the adjacent frame members of the opposite roof panels 98 and 99. The roof members 98 and 99 are also provided with spaced apertures which may, if desired, be internally screw threaded. These apertures are arranged so that an aperture in one roof panel registers with a corresponding aperture in the opposite roof panel and connecting members 100 are threaded into these registering apertures. Each connecting member has oppositely screw threaded end portions and a wrench receiving intermediate portion and after being threaded into the registering apertures is turned by a wrench to pull the two roof panels together to the condition illustrated in Fig. 13. Suitable cut outs 101 are provided in the roof panels adjacent the apertures receiving the connecting members 100 to permit manipulation of a wrench to tighten the members until the roof panels have been brought firmly together. Pulling the roof panels by the members 100 moves the hook receiving slots in the panels relative to the hooks carried on the upper edges of the end walls and the secondary partition members to force the roof panels tightly down against the upper edges of these wall and partition members and also forces the T-shaped members 95 into the apertures in the frame members 98 and 99 so that the roof panels are firmly connected to all of the partition walls and the end walls of the building.

After the roof panels have been brought firmly together, as illustrated in Fig. 13, projecting edge

5 portions 102 and 103 of the sheet metal coverings are folded together and cemented firmly down to form a seal as indicated at 104 in Fig. 13, which effectively prevents the entry of any moisture between the adjoining faces of the two roof panels.

10 Subsequently connecting members 105 are threaded into registering apertures in the roof panels and the corresponding side wall panels to pull the roof panels firmly down upon the top edges of the side wall members to seal these joints and further reinforce the building. The joints between all of the panels are sealed by 15 suitable gaskets as indicated at 84 and 85 in Fig. 10 so that the joints are air and moisture proof when the building is completely assembled. The floor panels rest upon suitable resilient gaskets 106, Fig. 15, carried by the supporting angle iron flanges so that the floor joints are also completely sealed.

20 In Fig. 11 there is illustrated a suitable roof gutter for association with the novel roof panels described above. In this construction the extending edge of the sheet metal cover 46 is bent over the edge of the panel and extended downwardly below the panel as indicated at 107 and may be braced against the panel by suitable tabs 108 if desired. A curved gutter or trough 109 is then secured to the under surface of the panel, as indicated at 110, and has its free edge 111 below the upper surface of the panel and is slightly spaced from the downwardly projecting portion 107 of the sheet metal cover. The relationship of the edge 111 to the cover portion 107 is such that, while water will flow downwardly along the roof panel and the portion 107 and into the gutter, debris, such as leaves, will not enter the gutter but will fall outside of the edge 111 and the gutter will thus not become choked by debris washed into it from the roof.

25 40 After the main structural units of the building have been assembled, as described above, the window openings and the exterior door opening are lined with suitable frames and the corners of the building are covered with corner beads. These window and door frames and corner beads 30 45 are preferably formed of lengths of extruded aluminum and are especially designed for the particular openings with which they are associated.

50 50 A special type of window for the improved housing unit is illustrated in Fig. 16. While this window is specially designed for use as a bathroom window, it may be used in other locations if desired.

55 55 In this construction a frame is provided having suitable edge members as indicated at 127 and 128 and internal members 129, 130, 131 and 132. The members 129 and 130 are parallel and spaced from each other and from the parallel edge members at substantially equal distances and the members 131 and 132 are perpendicular to the members 129 and 130 and spaced equal distances from each other and the corresponding parallel edge members. This provides a window 60 65 having nine comparatively small panes. Parallel spaced panes are placed in each opening one at each side thereof and are sealed in place and the spaces between the panes are filled with a suitable translucent insulating material. Crumpled cellophane or fiber glass has been 65 70 found to be particularly suited for this purpose. Preferably the center pane 133 is provided with a mirror surface so that it can be used as an indirectly illuminated mirror when desired.

75 While the interiors of the structural units or

panels will be sealed as perfectly as possible against the entrance of moisture and the frames will also be protected to some extent against temperature changes, it is desirable that the frame members should not be subject to any substantially hygroscopic expansion effects and that they should be as strong as possible so that they can be made of minimum size.

It will be obvious to those skilled in the art that various changes may be made in the invention without departing from the spirit and scope thereof and therefore the invention is not limited by that which is shown in the drawing and described in the specification but only as indicated in the appended claim.

What is claimed is:

A prefabricated building comprising prefabricated end and side wall panels having connecting means adjacent their outer edges, a prefabricated intermediate panel extending between said end walls and forming a partition, said intermediate and end panels having connecting means on their contiguous surfaces, prefabricated roof panels having connecting means along the portions abutting the upper edges of said side and end panels and meeting along adjoining edges positioned directly above the upper edge of said intermediate panel, and means connecting said adjoining edges and the upper edge of said intermediate panel comprising T-shaped elements secured in said upper edge and having their opposed arms engaging said adjoining edges and oppositely threaded elements engaging and drawing together said roof panels.
